FORM FOR MAKING LATEX ARTICLES

Abraham N. Spánel, Rochester, N. Y.

Application August 11, 1934, Serial No. 739,469

5 Claims. (Cl. 18—41)

This invention relates to latex garments as well as to forms for making the same.

This application is a continuation in part of the applicant's copending applications, Serial No. 5 684,549, filed August 10, 1933 now abandoned and Serial No. 696,037, filed October 1, 1933, Patent No. 2,015,632, dated September 24, 1935.

The main feature of the invention relates to latex garments, such as baby pants, which are 10 relatively inexpensive to manufacture, which are durable in construction and which are easy to apply to the wearer.

A further feature of the invention relates to 15 novel forms on which such garments can be made.

These and other features of the invention will appear from the detailed description and claims when taken with the drawings in which Fig. 1 is a front view of one style of garment made according to the present invention; Fig. 2 is a 20 side elevation of the same; Fig. 3 shows a slightly modified style of garment and Fig. 4 is a side elevation thereof; Fig. 5 is a vertical section taken substantially on the line 5—5 of Fig. 3; Fig. 6 is a fragmentary sectional view taken through the fastening openings in the garment and indicating the type of fastener that may be used therewith; Figs. 7 and 8 respectively show a front elevation and a side elevation of a preferred type 30 of form for making the garment shown in Figs. 1 and 2; Fig. 9 is a front elevation of still a different type of form which is suitable for making simultaneously two garments of the kind illustrated in Fig. 3; and Fig. 10 is a side elevation of this form; Fig. 11 is a section through this form taken substantially on the line 11—11 of Fig. 9; Fig. 12 is a fragmentary sectional view thereof taken substantially on the line 12—12 of Fig. 9; Fig. 13 illustrates a flat type of form on 40 which two garments can be made simultaneously; Fig. 14 is a vertical section of the same taken substantially on the line 14—14 of Fig. 13; and Fig. 15 is a fragmentary section through any of the forms of Figs. 9 to 14 inclusive, illustrating 45 a lateral margin of the form together with bosses for forming openings in the product and also a section through the product deposited on each side of the form.

Referring especially to Figs. 1 and 2, there 50 are illustrated a pair of baby's pants generally designated 5, made of deposited latex, rubber or like material. These pants which are shaped to conform to the body of the infant have an opening 6 in the top, where the latex at the margin of this opening is provided with a reinforced

edge 7 which is semipear-shaped in cross section (see Fig. 5). The pants are also provided with leg openings 8 and 9, the margin of each leg opening being reinforced by an accumulation of the material thereat which accumulation terminates in a feather or torn edge. At each side of the pants the material has a slit 12 therein which extends from the leg opening to the opening in the top of the pants. The latex at each margin of each slit is of increased thickness to 10 provide a reinforcement which terminates in a feather edge as indicated at 17, 17 in Fig. 6. At each side of the slit there are provided spaced pairs of openings 13, the edges of which openings are reinforced as shown at 19 in Fig. 6. These 15 openings are adapted to receive fastening means, such as buttons 14, although any suitable type of fastener other than buttons can be used without departing from the spirit of the invention. It will be noted that the leg openings 8 and 9 20 as shown in Fig. 1 face toward the front of the pants so that they tend to conform to the body of the infant while worn.

The modified style of the pants 15, shown in 25 Figs. 3, 4 and 5, differs from those illustrated in Figs. 1 and 2 in that the front and back of the pants are of identical shape, since no attempt has been made to shape them to the body of the infant. Also the leg openings are of different shape in that no attempt has been made to make 30 the pants tightly engage the legs of the infant during use. However, this style of pants lends itself to being manufactured on a simpler type of form. The top edge of these pants is also reinforced by a margin 16 which is semipear-shaped in cross section while the other free edges 35 of these pants are reinforced by accumulations or ridges of the material which terminate in feather or torn edges such as indicated at 17 (Fig. 6). Likewise, the material at the margins of the 40 button openings 18 is reinforced by an accumulation or ridge terminating in a feather or torn edge 19 similar to that shown at 17. However, the edge 19 may be formed by cutting, clicking or stamping out the portion of the layer within the 45 reinforcement. It will be understood that these pants are fastened on the infant by means of buttons such as 14 (Fig. 6) inserted in the registering pairs of openings 18.

The pants shown in Figs. 1 and 2 are made by 50 dipping a form 20 (Figs. 7 and 8) one or more times into a bath of liquid latex, such as an aqueous dispersion of rubber, with a suitable drying interval between each of the dippings. The form 20, which has a generally rounded out- 55

line is provided at its lower edge with a pair of fins 21 adapted to be received in the female portion of a rack (not shown) so that a plurality of forms may be dipped simultaneously. The 5 front face of the form as viewed in Fig. 7 is generally flat, whereas, the rear surface 21 indicated by the dotted line in Fig. 8 is dished or concave to provide an increased area of the layer deposited thereon, so that the pants will be 10 shaped to the body of the infant. The upper edge of the form as shown in these views is provided with raised portions or bosses 22 which are generally of flattened elliptical outline, which rise abruptly from the surface of the form, and 15 which terminate in an abrupt edge 24. The lower margin of the form also terminates in an abrupt edge 25, being defined by intersecting surfaces. Each boss 22 is connected to the abrupt edge 25 of the form by a fin 26 which projects 20 abruptly from the form and each exposed corner thereof is abrupt or sharp for purposes to be defined. A series of circular bosses 28 also project abruptly from the form and also terminate in an abrupt or sharp edge similar 25 to that shown at 29 of Fig. 15. These bosses are arranged in pairs, each pair being separated by a fin 26.

In making of pants on the form shown in Figs. 7 and 8, the form is submerged into the mentioned bath of latex and then slowly removed therefrom. Then the form with the deposited layer thereon is held with its abrupt edge lowermost and with this edge in a substantially horizontal position until the deposited layer is dried. 35 Thereafter, the form is again dipped and the form removed from the bath and held with the abrupt edge 25 substantially horizontally as before mentioned until the second layer is dried. These operations are repeated until a garment 40 of the desired thickness is formed. Although it has been mentioned that layers are thus deposited, the finished product does not disclose such layers but appears to be a homogeneous mass. When a product of the desired thickness 45 has thus been deposited, dried and/or cured, the portions of the layer on the faces of the bosses 22 and the ribs 26 are stripped or torn away leaving the leg openings 8 and 9 and the lateral slits 12 with the margins thereof reinforced by 50 a ridge or accumulation of latex terminating in a feather or torn edge. However, the edge of the product deposited adjacent the abrupt edge 25 will be reinforced by an accumulation of the material similar to one-half a tear drop in cross 55 section, and the excess product present on the fins 21 is stripped away as far as the abrupt edge 25. The portions of the deposited layer on the ends of the bosses 28 are torn away to 60 provide the desired openings 13 in the product. The remaining operations of treating the product, preparing it for market are similar to those well-known in the art and need not be herein set forth.

The garment shown in Figs. 3, 4 and 5 can be 65 made on the form 30 of Figs. 9, 10 and 11. This form is generally saddle-shaped and is adapted to making two garments thereon simultaneously, since the form is hollow. This form comprises 70 two flat panels 31 and 32 which are joined together by the curved upper portion of the form. The lower edges of the form, however, are abrupt, while the other margins thereof are bounded by raised borders 33, 34, which are generally rectangular in cross section, although this cross

sectional shape is not essential as long as the border rises abruptly from the junction 35 (Fig. 11) of the form. As illustrated the borders 33 and 34 have abrupt edges 36. A series of circular bosses such as 37 project from both faces 5 of the form adjacent each border to define buttonholes in the resulting garment. Supports 38 project from the sides of the borders of the form and serve to suspend it during the dipping operations.

In making a garment on this form, the form is dipped one or more times, with a drying interval intervening in the latter case, into a bath of liquid latex, until a layer of the desired thickness is accumulated, dried and/or cured on the surfaces of the form. The excess portions of the layer on the surfaces of the borders 33 and 34 are torn or stripped away as far as the abrupt edge 36 and also from the faces of the lugs 37, leaving an accumulation of reinforcement of the 20 layer in the junction of these parts with the main body of the form. At the abrupt edges of these parts, however, the garment will have a torn or feather edge. However, on the extreme lower edges of the form, the layer will accumulate a reinforcement which is substantially semi-pear-shaped in cross section as indicated at 25 45 in Fig. 14. It will be understood that two similar garments are made simultaneously on the form, the garment made on the inside of the 30 form being somewhat smaller.

A garment similar to that shown in Figs. 3, 4 and 5 except that it is in no way shaped to the body of the wearer, can be made on the flat form 40 illustrated in Figs. 13 and 14. Form 40 35 is also adapted to make two garments simultaneously, one garment being made on each face of the form. This form differs from that shown in Figs. 9, 10 and 11 in that it is a flat plate with all of its edges except the lower edge 41 bounded 40 by a border 42 which is identical in character with the borders 33 and 34 in the last described form. The form also has circular bosses 43 projecting from the face thereof, to define buttonholes in the resulting garment.

A pair of garments can be made on this form in accordance with the processes already described. It will be understood, however, that the uppermost edge 44 of the deposited garments will have a cross section similar to that shown in Fig. 14 and will terminate in a torn or feather edge. The lower portions of the garments deposited on this form, however, have reinforcements substantially identical with the shape indicated at 45 in Fig. 14.

While several embodiments of the invention have been disclosed, it will be understood that this invention is capable of still further modifications and that this disclosure is intended to cover any variations, uses, or adaptations of the 60 invention falling within the scope of the appended claims.

What I claim is:

1. A form for making latex pants or the like by dipping, comprising a panel having a constricted intermediate portion, said panel being bounded at substantially its entire margin by an abrupt edge.
2. A form for making latex pants or the like by dipping, comprising a plate having a panel on each surface thereof, each panel having a constricted portion and being bounded by an abrupt edge.
3. A form for making latex pants or the like by dipping, comprising a flat panel having a con-

stricted intermediate portion and being bounded by an abrupt edge.

4. A sheet-like form for making a latex article on each of the opposite surfaces thereof simultaneously by deposition, said form having similar article-defining outlines on each surface thereof, and marginal reinforcement-generating means for each surface of the form.

5. A sheet-like form for making a latex article on each of the opposite surfaces thereof simultaneously by deposition, said form comprising a plate folded transversely upon itself and having similar article-defining outlines on each surface thereof, and marginal reinforcement-generating means for each surface of the form.
